UNITED STATES PATENT OFFICE

CHRISTIAN PFEIFFER, OF HARTFORD, AND FREDERICK T. MOORE, OF EAST HARTFORD, CONNECTICUT, ASSIGNORS TO COLT'S PATENT FIRE ARMS MANUFACTURING CO., OF HARTFORD, CONNECTICUT, A CORPORATION OF CONNECTICUT

TRIGGER MECHANISM FOR MACHINE GUNS

Application filed December 14, 1928. Serial No. 325,956.

The general object of the invention is to provide an improved trigger mechanism which is so constructed as to prevent automatic continuous firing of the gun and which requires the trigger to be separately moved for the firing of each shot. More specific objects of the invention are to provide certain novel and improved details of construction whereby the foregoing general object is attained.

The invention is particularly applicable to firearms of the type set forth in the patents to J. M. Browning No. 1,525,065 and 1,525,066 both dated February 3, 1925 and in the accompanying drawings we have illustrated the inventions as applied to a firearm of this type. It will be understood, however, that the drawings are intended for illustrative purposes only and are not to be construed as defining or limiting the scope of the invention, the claims forming a part of this specification being relied upon for that purpose.

Of the drawings:

Fig. 1 is a fragmentary vertical longitudinal sectional view of a firearm embodying the invention.

Fig. 2 is an enlarged fragmentary longitudinal sectional view showing the trigger mechanism in a position different from that shown in Fig. 1.

Fig. 3 is a view similar to Fig. 2 but showing the parts of the gun in a still different position.

Fig. 4 is a fragmentary plan view of the parts shown in Figs. 2 and 3 the position of the parts, however, being as shown in Fig. 1.

Figs. 5 and 6 are plan and side views respectively of parts of the trigger mechanism separated from other parts of the gun.

Fig. 7 is a front view of the parts shown in Figs. 5 and 6 this view being partly in section along the line 7—7 of Fig. 6.

Fig. 8 is a fragmentary perspective view of the parts shown in Figs. 5 to 7 together with immediately associated parts of the firearm.

In Fig. 1 we have illustrated a portion of a gun of the type set forth in the before mentioned Browning patents. Reference can be had to the said patents for a detailed description of the gun mechanism. For present pur-

poses it is sufficient to point out that the gun comprises a main casing 1 generally rectangular in cross section, and a lock frame or member 2 which is longitudinally reciprocable in the casing, this member moving rearward upon recoil and automatically returning to its normal forward position after recoil. Carried by the reciprocable member 2 so as to be bodily movable therewith is a trigger lever or operating element 3 and also carried by the reciprocable member 2 is suitable mechanism operable when the said member is in its forward position for effecting the firing of the gun upon the movement of the said operating element 3 relatively to the reciprocable member. As shown, the operating element 3 is pivoted at 4 for rearward movement to effect the firing of the gun, but we do not necessarily limit ourselves to an operating element which is so movable.

Movably mounted on the casing 1, preferably at the top thereof, is a trigger bar 5 and when the operating element 3 is movable rearwardly to effect firing the trigger bar 5 is also movable rearwardly so as to be adapted to cause the required rearward movement of the element 3. As shown the trigger bar 5 is mounted for longitudinal movement and is operatively connected at the rear with a trigger 6 pivoted to the top wall of the casing 1 for movement about a vertical axis. The trigger bar 5 has an upward extension 5^a which projects into a slot in the trigger. A transverse pin 7 secured to the extension 5^a prevents the rear end of the trigger bar from dropping down. As shown most clearly in Fig. 8 the forward end of the trigger bar 5 is normally supported directly upon an inward extending flange 8 of the main casing 1, this flange having a longitudinal groove 9 into

which projects a tongue 10 on the left hand part of an enlarged head 11 formed on the bar 5. The right hand part of the head 11 is so located as to engage the upper end of the operating element 3 when the trigger bar is moved rearward, this relationship of the parts being clearly shown in Fig. 4. From the foregoing description it will be apparent that when the trigger 6 is moved rearward the trigger bar 5 is similarly moved rearward, 100

the right hand portion of the head 11 engaging the operating element 3 to move it backward and thus effect the firing of the gun.

In the construction as shown in the Browning patents referred to continuous or volley firing of the gun may be caused by merely holding the trigger and trigger bar in their rearward positions. The reciprocable element 2 and all of the parts carried thereby move rearward upon recoil, cocking of the gun being then effected and the operating element 3 resuming its normal position with respect to the said member 2. With the trigger bar held in its rearward position the element 3 would be immediately reengaged by the trigger bar upon return of the member 2 and associated parts to their forward positions. This continuous or volley firing is desirable under some circumstances but under other circumstances it is preferable to place the firing entirely under the control of the trigger and to so construct and arrange the parts that the firing of each shot can be effected only by a separate movement of the trigger.

In accordance with the invention we provide a means dependent upon the movement of the trigger in the firing direction, ordinarily in the rearward direction, for effecting a transverse movement of the trigger bar or at least of the portion 11 thereof which engages the operating element. This engaging portion 11 is moved transversely out of the path of the operating element so that the said element is not engaged when it returns to its forward position. As illustrated there is provided a bracket 12 which is secured to the flange 8 and which is formed with a lug 13 having a bevelled cam surface 14 adapted to engage a similar cam surface 15 on the left hand part of the head 11. It will be obvious that as the trigger bar is moved rearward the surface 15 engages the surface 14 with the result that the forward portion of the trigger bar is cammed upward to the position shown in Fig. 2. A part of the rear portion of the trigger bar is cut away or relieved at 16 to permit this upward swinging of the forward portion of the bar.

In order to hold the trigger bar out of the path of movement of the operating element during the return movement of the bar in the forward direction we provide a plunger 17 which is slidably mounted in a suitable hole in the bracket 12 and which is normally pressed laterally to its outer position by means of a spring 18. The plunger is provided with a ledge 19 which is automatically pushed under the left hand edge part 11^a of the head 11 as soon as the said head has been sufficiently raised by means of the cam surfaces 14 and 15 as already described. This ledge 19 on the plunger 17 serves to support the trigger bar during its forward return movement.

At the conclusion of its forward movement

the head 11 passes beyond the ledge 19 on the plunger 17 and is thus free to return downward to its normal position. In order to positively ensure the downward movement of the head 11 there is provided a spring pressed plunger 20 mounted in a vertical hole in the bracket 12. This plunger bears against the upper surface of the trigger bar 5, being forced upward in opposition to its spring when the trigger bar is raised by reason of the action of the cam surfaces 14 and 15. At the conclusion of the forward movement of the trigger the plunger 20 pushes the trigger bar downward to its normal position.

In order that the ledge 19 on the plunger 17 may not interfere with the normal rearward movement of the trigger bar the said head 11 is provided with a bevelled surface 21 which is adapted to engage the said ledge 19 and force the plunger inward in opposition to its spring.

From the foregoing description it will be apparent that when the trigger bar 5 is moved rearward in the usual way by the trigger 6, the forward end of the bar including the head 11 is raised by the cam surfaces 14 and 15 and that during this rearward movement the two plungers 17 and 20 are forced inward in opposition to their respective springs. As soon as the head 11 is sufficiently raised the ledge 19 on the plunger 17 snaps under part 11^a of the head 11, thus positively holding the trigger bar in its upper position. The head 11 is so held during the forward return movement of the trigger bar, but as the bar approaches its forward position it is released by the ledge 19 and is then forced downward by the plunger 20. Thus the forward portion of the trigger bar is held in its upper position out of the path of movement of the operating element 3 when at or near its rearward position. It can be re-engaged with the element 3 only by being first moved forwardly sufficiently to be disengaged by the ledge 19. It therefore follows that the gun can be fired only by effecting a complete movement of the trigger and associated parts and cannot be fired continuously by merely holding the trigger in its rearward position.

In order to positively assure the upward movement of the trigger bar sufficiently to permit its engagement by the ledge 19 we prefer to provide auxiliary means carried by the reciprocable member for positively causing the said upward movement. As shown this means is in the form of a cam 22 secured as a matter of convenience to the carrier cam 23 which is rigidly connected with the said reciprocable member 2. The cam 21 is so positioned as to engage the right hand part of the head 11 and to positively force it upward as clearly indicated in Fig. 3. From the foregoing description it will be apparent that even if the operator should fail to move the trigger bar rearward sufficiently to cause the

engagement of the ledge 19 with the part 11^a, such engagement would be positively brought about by the cam 22 moving rearwardly upon recoil.

5 What we claim is:

1. In a trigger mechanism for a semi-automatic gun, the combination of a longitudinally reciprocable member movable rearward upon recoil and automatically returning to its normal forward position, an operating element bodily movable with the said member and also movable relatively thereto, mechanism operable when the reciprocable member is in its forward position for firing the gun upon the relative movement of the operating element, a trigger bar manually movable from its normal position and having a portion adapted upon such movement to engage and move the operating element to fire the gun, means dependent upon the said movement of the trigger bar for effecting a transverse movement of at least the said engaging portion thereof out of the path of movement of the operating element, and automatically operative means for holding the said portion out of the said path during the return movement of the trigger bar to its normal position.
2. A trigger mechanism as set forth in claim 1, wherein the operating element and the trigger bar are both movable in the rearward direction to effect firing.
3. A trigger mechanism as set forth in claim 1, wherein there is provided a stationary inclined cam surface adjacent the engaging portion of the bar and serving to effect the said transverse movement thereof, and wherein there is a spring-pressed plunger engaging the bar to oppose the said transverse movement and to return the bar to normal position at the conclusion of the return movement thereof.
4. A trigger mechanism as set forth in claim 1, wherein the said automatically operative means is a transversely movable plunger spring-pressed toward its operative position, and wherein there are means dependent on the firing movement of the bar for forcing the plunger backward in opposition to its spring.
5. A trigger mechanism as set forth in claim 1, wherein the said automatically operative means is a transversely movable plunger spring-pressed toward its operative position, and wherein the trigger bar is provided with a cam surface engaging the plunger to force it backward in opposition to the spring during firing movement of the bar.
6. In a trigger mechanism for a semi-automatic gun, the combination of a longitudinally reciprocable member movable rearward upon recoil and automatically returning to its normal forward position, an operating element bodily movable with the said member and also movable rearward relatively

thereto, mechanism operable when the reciprocable member is in its forward position for firing the gun upon the relative rearward movement of the operating element, a trigger bar manually movable rearward from its normal position and having a portion adapted upon such movement to engage and move the operating element to fire the gun, a stationary cam serving during rearward movement of the trigger bar to effect a transverse movement of at least the said engaging portion thereof out of the path of movement of the operating element, a spring-pressed plunger for holding the said portion out of the said path during the return movement of the trigger bar to its normal position, means dependent on the rearward movement of the bar for forcing the plunger backward in opposition to its spring, and a second spring-pressed plunger acting in a direction at a right angle to that of the first plunger for engaging the trigger bar to oppose the transverse movement thereof and to return the bar to normal position at the conclusion of the forward return movement thereof.

7. In a trigger mechanism for a semi-automatic gun, the combination of a longitudinally reciprocable member movable rearward upon recoil and automatically returning to its normal forward position, an operating element bodily movable with the said member and also movable relatively thereto, mechanism operable when the reciprocable member is in its forward position for firing the gun upon the relative movement of the operating element, a trigger bar manually movable from its normal position and having a portion adapted upon such movement to engage and move the operating element to fire the gun, means dependent upon the said movement of the reciprocable member during recoil for insuring a transverse movement of at least the said engaging portion of the trigger bar out of the path of movement of the operating element, and automatically operative means for holding the said portion out of the said path during the return movement of the trigger bar to its normal position.

8. A trigger mechanism as set forth in claim 7, wherein the operating element and the trigger bar are both movable in the rearward direction to effect firing.

9. A trigger mechanism as set forth in claim 7, wherein the operating element and the trigger bar are both movable in the rearward direction to effect firing, and wherein the said means for insuring transverse movement is a cam secured to the reciprocating member and directly engaging the trigger bar.

10. In a trigger mechanism for a semi-automatic gun, the combination of a longitudinally reciprocable member movable rearward upon recoil and automatically return-

ing to its normal forward position, an operating element bodily movable with the said member and also movable relatively thereto, mechanism operable when the reciprocable member is in its forward position for firing the gun upon the relative movement of the operating element, a trigger bar manually movable from its normal position and having a portion adapted upon such movement to engage and move the operating element to fire the gun, means dependent upon the said movement of the trigger bar for effecting a transverse movement of at least the said engaging portion thereof out of the path of movement of the operating element, means additional to the last aforesaid means and dependent upon the rearward movement of the reciprocable member for insuring the said transverse movement of the said engaging portion of the trigger bar and automatically operative means for holding the said portion out of the said path during the return movement of the trigger bar to its normal position.

11. A trigger mechanism as set forth in claim 10 wherein the operating element and the trigger bar are both movable in the rearward direction to effect firing.

12. A trigger mechanism as set forth in claim 10, wherein the operating element and the trigger bar are both movable in the rearward direction to effect firing, and wherein the said additional means for insuring transverse movement is a cam secured to the reciprocating member and directly engaging the trigger bar.

In testimony whereof we have hereunto set our hands this 12th day of December, 1928.

CHRISTIAN PFEIFFER.
FREDERICK T. MOORE.
